WASHING APPARATUS

Francis John Osuch, Grosse Pointe, Mich., assignor to Robot Products Corporation, Detroit, Mich., a corporation of Michigan

Application November 22, 1938, Serial No. 241,819

2 Claims. (Cl. 68—13)

This invention relates to washing apparatus. One of the objects of my invention is to provide a combination washing tub and removable sink nested in the upper portion thereof and to provide an effective sealing joint between the two so as to prevent leakage of water from the sink drainboard into the washing tub.

Another object of my invention is to provide a new and improved type of sink pan which may be constructed of very thin gauge sheet metal without the provision of a bead about its upper peripheral edge and to reinforce the lower portion of the sink to prevent the distortion of the walls of the pan.

Another object of my invention is to provide an improved type of agitating mechanism which has provisions for permitting drain water to pass therethrough and provides for guiding and receiving a bar element for actuating the agitator.

Another object of my invention is to provide in a combination sink and tub an improved system of draining both the sink and the tub.

Further objects and advantages of the present invention will be apparent from the following description, reference being had to the accompanying drawings, wherein a preferred form of the present invention is clearly shown.

In the drawings:

Fig. 1 is a fragmentary plan view of the apparatus embodying my invention;

Fig. 2 is an enlarged side view in elevation partly broken away of the apparatus shown in Fig. 1;

Fig. 3 is an enlarged fragmentary view in cross section showing the sealing connection between the large tub and the sink nested in the upper portion thereof;

Fig. 4 is a plan view of the agitating means shown in Fig. 2;

Fig. 5 is a fragmentary view of a driving motor in operative relation with the agitating means;

Fig. 6 is a side view in elevation of a modified form of the apparatus showing features of my invention;

Fig. 7 is an enlarged fragmentary view of a portion of the apparatus shown in Fig. 6;

Fig. 8 is a fragmentary view of a modified form of agitating means embodying features of my invention and shown in combination with the deep tub and sink;

Fig. 9 is a view taken along the lines 9—9 of Fig. 8;

Fig. 10 is a view in cross section of a modified form of apparatus embodying features of my invention;

Fig. 11 is a view similar to that shown in Fig. 7 of a modified form of apparatus embodying features of my invention;

Fig. 12 is a view taken along line 12—12 of Fig. 11; and

Figs. 13 and 14 are fragmentary views of a modified form of sink.

Referring now to the drawings, the numeral 20 designates in general a combination tub, sink and agitating apparatus embodying features of my invention. The apparatus 20 includes tub 22, sink 24 and the agitator 26. The tub 22 is secured to a drainboard 28 by means of bolts 30. The bolts 30 secure flanges 32 of tub 22 to metallic angle iron 34. The drainboard includes sheet metal material 36 which is preferably stainless steel and this is formed to provide a raised bead 38 about the outer edge of the drainboard to prevent water from flowing over the drainboard surface. The drainboard also includes a downwardly extended portion 40 and a return bend portion 42. The return bend portion 42 is preferably secured to a supporting block 44 by screws (not shown). The angle iron member 34 extends over the block 44 and is preferably secured thereto by screws (not shown). The block 44 may be of any suitable material, such as metal, wood or ply wood. Between the angle iron member 34 and the flange 32 there is clamped a soft rubber gasket member 46 which provides a resilient connection between the tub and the drainboard, and this rubber gasket material also serves for sealing the sink 24 and the tub 22 to prevent seepage of water from the drainboard surface 36 into the large tub 22. The drainboard portion 36 includes a downwardly extended portion 48 which is curved rearwardly to extend into the rubber 46. This downwardly extended portion 48 is tapered or inclined to correspond to the tapered or inclined surface of pan 24. By this arrangement, the sink pan is sealed by engagement with the portion 48 and also with the rubber portion 46. The sink pan 24 may be provided with a handle 50 for lifting the sink pan from the tub when it is desired to place articles in the deep tub for washing.

The sink pan as shown includes side walls which are of thin gauge sheet metal material and are of uniform thickness from the bottom wall to the upper peripheral edge of the pan. In order to provide a pan of this type construction which is of sufficient rigidity that the side walls will not distort and fail to retain their original shape to effect sealing relation with the gasket 46 and the member 48, I have provided a return bend por-

tion 54 in the bottom of the pan so as to add such rigidity thereto.

When it is desired to utilize the deep tub for washing dishes or clothes therein, the sink pan 24 is removed from the tub and an electric motor 56, carried by a closure 58, is inserted in the upper part of the tub. The motor 56 includes a shaft 60 which is adapted to be received in the upper portion of the agitator for actuating said agitator. The motor may be of continuous rotary type or of the oscillating type, or these two types combined. Motors of this type are well known and further description thereof is deemed unnecessary. If desired, the motor 56 may be mounted directly upon the upper surface of the bottom wall of the sink pan 24 for actuating the agitator. In this case a shorter shaft for the motor may be used.

The agitator has a circular base portion 64 and a vertically extending passage 66. This passage is in direct alignment with an outlet opening 68 in the sink pan 24. The opening 68 is covered by a removable plug 70. Thus, when it is desired to drain the sink pan, the plug 70 may be removed and the water in the sink will flow into the passage 66 whence it passes to a drain connection 72. Within the passage 66 is provided a bearing 74 which is preferably square in horizontal cross section for receiving the shaft 60 of motor 56. Immediately above the bearing, the passage 66 diverges outwardly as at 76 to provide a definite taper for guiding the shaft 60, which is preferably square in horizontal cross section so that as it approaches the bearing 74 it will be in proper alignment to be received therein. The agitator is provided with two blades 80. However, if desired, any additional number of blades may be provided. On the lower surface of the agitator is provided a bearing 86 which cooperates with the drain connection 72 to seal the tub against leakage into the drain connection 72.

The drain connection 72 is in open communication with the drain conduit 90 which is connected to the conventional drain pipe 92. This completes a drain connection from the sink pan 24 to the drain pipe 92. However, in order to drain the tub 22, I provide a drain connection 94 and drain conduit 96 which is connected to drain pipe 92 by a valve mechanism 98. The valve mechanism is controlled by a rod 100 having a handle portion 102 above the drainboard surface 28. The handle 102 may be actuated to permit the water to flow from the tub 22 or retain it therein in the well known manner.

In Figs. 6 and 7, I have shown a modified form of an apparatus wherein the sink pan 124 is nested in the deep tub 126. This sink pan and tub correspond to the sink pan 24 and tub 22. The manner of connection between the two is somewhat different, however. In this embodiment of the invention, the sink pan is provided with a laterally extended flange 128 which is adapted to engage a hollow rubber gasket member 130 for sealing the connection between the tub and sink pan. The gasket 130 is provided with a tail portion 132 which is clamped to the tub by bolts 134. If desired, however, the tail portion 132 may be omitted and the hollow gasket 130 may be secured to the flange 128 of pan 124 by cement or other material. The pan 124 is provided with a raised portion 135 which carries a handle 136. This raised portion is formed merely by conventional type of punch and die mechanism which inwardly depresses the portion 135 from angular side wall 138. This leaves a space 139

which permits open communication to the pan 124 and the tub 126 to serve as an overflow drain from the sink pan 124. To the side of the tub 126 is provided a casting 140 which has inwardly directed portion 141 which conforms to the curvature of the pan 124 for receiving drain water from the pan 124 through perforations 142 therein. Thus, the drain water from the pan may pass through the perforations 142 into casting 140, which has secured thereto a drainpipe 144. The tub 126 has a drain connection 150 controlled by valve mechanism 152. For operation of the valve mechanism 152, I have provided a rod 160 which has a handle portion 162 attached thereto extending above the drainboard of the tub. The drainpipe 144 leads to a conventional drainpipe 154 below the valve mechanism 152.

In Figs. 8 and 9 I have shown another form of agitating mechanism wherein a drain pipe 170 is secured to a drain connection 172 in the lowermost portion of the tub 174. The drainpipe 170 extends upwardly into the tub 174 and an agitator 178 is positioned within the tub 174 and surrounds the pipe 170. The agitator 178 includes a hollow passage 180 which surrounds the pipe 170. The agitator includes a vertically extending tubular portion 182 to which is secured agitating vanes 184. A disc shaped member 186 is associated with the blades or vanes 184 in the tubular portion 182. Below the disc shaped member is a bearing 188 which cooperates with the drain connection to provide bearing surfaces. The upper portion of the agitator is provided with a hollow portion 192 which is adapted for receiving a shaft 35 of an electric motor (not shown) for driving the agitator in the similar manner to that disclosed in Fig. 5. Also, in the upper portion of the agitator is provided V-slots 194 for receiving any suitable projection, such as a pin (not shown) upon the agitating shaft of said electric motor so as to provide a driving connection between such motor shaft and the agitator. As will be noted, the agitator has a passage extending throughout its vertical length, and this passage is in alignment with an outlet passage 200 of a removable sink pan 201. Thus, drain water from the sink 201 may pass through hollow portion 192, passage 204, into the drain pipe 170, whence it passes through the drain casting 172 to the conventional drain.

From the foregoing, it will readily be apparent that I have provided an improved combination tub, sink and washing apparatus wherein the sink and tub are effectively sealed, and that the sink may be made of thin gauge sheet metal material without distortion, and that the sink may be readily removed to permit driving mechanism to engage the agitating mechanism in the tub, and that the agitating means is so designed as to readily receive the driving mechanism, and is provided with a hollow portion to facilitate the drainage of the sink therethrough. In devices of the type herein described, the sink pan is readily removable to give access to the agitating means and the sink pan may be taken to the dining table for removing the dishes therefrom to be carried and inserted into the tub for washing said dishes. The tub may also be used for washing clothes if desired. Any suitable rack which conforms to the curvature preferably of the agitator may be inserted into the deep tub for holding the dishes therein.

While I have designated certain specific materials to be used in connection with the construction of my apparatus, it will be understood that many other materials may be substituted in

certain instances. For example, instead of using stainless steel for the sink drainboards, "micarte," linoleum and the like may be used. Other types of resilient material may be used for the gaskets besides soft rubber, such as closely woven fabrics or other material.

In Fig. 10 I have shown sink 200 and drain pipe 170 connected by a removable funnel 210. This funnel may be of any desired shape for conducting the drainage from the sink to the drain pipe when the agitator 178 is not used.

In Figs. 11 and 12, I have shown apparatus similar to that shown in Figs. 6 and 7. In these figures of the drawings, 226 is the deep tub which corresponds to tub 126 and sink 228 corresponds to sink 124. In this embodiment of the invention, however, the sink 228 has secured thereto a casting 230 which is V-shaped so that the lower end will be wide enough to receive the drainage from the sink through perforations 234 in the sink while the upper portion is wide enough to receive the overflow from the sink about its handle 238 and through space 240 in which the handle is pivoted. The tub 226 is cut away as at 244 to receive the casting 230. Thus, the sink is readily insertable and removable from the tub. On the outside of the tub, there is secured a tapered casting 250 for receiving the drainage from the sink through perforations 234 and space 240 and for conducting such drainage to drain pipe 254 which corresponds to pipe 144. In this embodiment of my invention, the outwardly directed flange 256 of sink pan 228 terminates a short distance from sink drainboard 258 to allow drainage from the drainboard into castings 230 and 250. On opposite sides of the casting 230 is provided gaskets 260 similar to the hollow gasket portion 130 shown in Fig. 7. This gasket may be secured to flange 264 of tub 226 or to flange

256 of sink 228 as desired to prevent drain water on the sink board from entering tub 226.

When it is desired to construct a sink pan like the one shown in Fig. 3 with a rolled bead about its upper peripheral edge, it may be constructed as shown in Figs. 13 and 14. In these figures a sink pan 265 corresponds to sink pan 24, but has a bead 267 which is rolled inwardly. The bead is cut away at 270 to provide for receiving a handle 272. The handle 272 includes portions 274 pivoted under the bead 267.

Although only a preferred form of the invention has been illustrated, and that form described in detail, it will be apparent to those skilled in the art that various modifications may be made therein without departing from the spirit of the invention or from the scope of the appended claims.

I claim:

1. Washing apparatus comprising a tub having an opening, a drain pipe positioned in said opening and extending upwardly into said tub, a sink positioned in the upper part of said tub and having a drain outlet, and hollow agitating means surrounding said pipe and having a portion directly thereover and in communication with said drain outlet.
2. A device of the character described comprising a tub having an opening in its bottom wall, a drainpipe extending into said tub through said opening, agitating means surrounding said drainpipe in said tub, and a removable sink pan in the upper portion of the tub and having a drain outlet, the upper portion of said agitating means having a passage in communication with said drain outlet and said drainpipe and being constructed and arranged to receive driving mechanism for said agitating means.

FRANCIS JOHN OSUCH.
